Filed Nov. 21, 1967, Ser. No. 9,493

Term of patent 14 years

U.S. Cl. D9—145
Int. Cl. D9—01

FIG. 1 is a perspective view of a combined bottle and closure therefor embodying my new design;

FIG. 2 is a top plan view on an enlarged scale;

FIG. 3 is a bottom plan view on an enlarged scale; and

FIG. 4 is an exploded elevational view thereof on an enlarged scale showing the closure removed from the bottle.

The dominant features of my design reside in the portions shown in full lines.

I claim:

The ornamental design for a combined bottle and closure therefor, as shown and described.
